BOAT PROPULSION APPARATUS

Adolph Ronning, Minneapolis, Minn.

Application April 15, 1938, Serial No. 202,258

5 Claims. (Cl. 115—17)

This invention relates generally to improvements in outboard motors such as used for the propulsion of water craft of various kinds.

These motors derive their name from the fact that they are supported in an outboard fashion from the rear or other portion of the boat, and they conventionally embody an internal combustion motor equipped with a mounting bracket for supporting it upon the boat and with its power shaft depended to a transmission unit which operates below the water level and drives the propeller in the water. The engine is cooled by the circulation of water through a suitable jacket and this water is conveniently and logically obtained directly from the body of water in which the boat is operated. The water is circulated around the heated parts and is then discharged and replaced by cool water so that the circulation is in a constant stream with no recirculation whatever required. The cooling water is ordinarily forced through the cooling system by a water pump driven in some manner by the motor; and, inasmuch as the water is picked up and discharged below the water level in which the boat is operating, both the water inlet and outlet and the circulating pump is ordinarily located in the transmission unit aforesaid. Also associated with the transmission unit is the exhaust means for the motor which is desirably arranged to discharge the exhaust gases below the water level in order to reduce the exhaust noises of the motor.

My invention particularly provides improvements in the water circulating and exhaust discharging systems and functions of the motors as above defined, and the primary object is to provide a cooperating assembly and means whereby the water may be circulated more efficiently and without the aid of a mechanical water pump, and in which the exhaust gases are caused to be so discharged that noise will be substantially eliminated, and complete scavenging of the motor will be carried out at all times.

Another object is to provide means whereby the exhausted gases and discharged cooling water are caused to be ejected through the hub portion of the propeller in a rearward direction substantially along the axis of rotation of the propeller. As a result there occurs a very considerable outward suction at the point of egress of the gases and water such that they will be forcibly drawn from the motor. This suction is brought about by the action of the propeller in the water by which its blades tend to urge the water outwardly and rearwardly, causing at

least a partial vacuum to be formed immediately to the rear of the hub where the gases and waste water are ejected.

A further object is to provide an assembly as set forth above in which the exhaust noise from the motor may be completely or substantially eliminated due to the discharge of the gases into the turbulent water to the rear of, and surrounding, the propeller so that the volatile gases will be broken up very finely and the noise more efficiently absorbed and eliminated.

A further object is to provide a motor assembly of the kind in which no mechanical water pump need be used, thus preventing damage by freezing, and in which the enclosing housing parts of the transmission unit are effectively streamlined to reduce water resistance and drag to a minimum, and sloped to have a rudder effect to facilitate steering.

Another object is to provide an attachment for a conventional transmission unit and enclosed water circulating system, by the use of which the exhaust gases may be carried out through the propeller hub as, and for the purposes, described, and which attachment is so formed and arranged that it will offer very little resistance to travel through the water.

Still a further object is to provide blower means assembled in the propeller hub and so arranged that the exhaust gases will be forcibly drawn from the engine by action of the propeller, and which blower means serves to discharge the gases outwardly and rearwardly along the axis of rotation of the propeller to thus reduce noise in the manner hereinbefore set out. This structure thus provides both an actual power suction as well as the pulling effect of the vacuum behind the propeller upon the exhaust gases.

The foregoing and other more specific objects of my invention, together with means whereby the same may be carried into effect, will be made apparent in the course of the following detailed specification, reference being had to the accompanying drawings wherein:

Fig. 1 is a side elevation of an outboard motor constructed and assembled in accordance with my invention.

Fig. 2 is an enlarged vertical and longitudinal section through the lower portion, or transmission unit, of the assembly, and showing the attachment for a conventional structure of this kind by the use of which attachment the exhaust gases may be carried out through the propeller hub.

Fig. 3 is an enlarged cross section along the line 3—3 in Fig. 2.

Fig. 4 is a fragmental sectional elevation of a propeller having interior suction blades designed for use in the assembly of Fig. 2, for drawing the exhaust gases out through the hub of the propeller.

Referring now with more particularity to the drawings, the reference character A designates the motor which may be of any conventional type and which includes the depended tubular standard or member B journaled at C in a bracket D by which the motor is supported in "out-board" fashion on the boat. The motor may thus be oscillated about a vertical axis on the bracket D by manipulation of the handle E, and the bracket is so arranged that it permits tilting adjustment and movement of the water in usual manner and for usual purposes. For convenience in this description, however, it will be assumed that the motor is operated with the standard B vertically disposed and depended into the water.

Affixed to the lower end of this standard B by the clamp F is the transmission unit G, and the drive shaft H of the motor depends through the standard B into this unit G for the purpose of driving the propeller shaft J which is horizontally disposed and extended in a fore and aft direction. The actual driving connection is made through bevel gears K and, of course, the shafts H and J are suitably journaled in bearings L and are provided with oil seals M so that the chamber N may be oil filled to lubricate the parts. A conventional water pump O is arranged in the unit G and includes a piston P which is reciprocated by the cam Q on the propeller shaft J and operates to draw in water at R and discharge it at S into a tube T which carries it to the motor A from which it is discharged in any suitable manner after passing through the cooling jackets. The cam Q is releasably or retractably held by the spring U so that the pump will not be broken should it freeze up in cold weather.

The foregoing constitutes a conventional outboard motor assembly upon which my invention is employed, and I provide therefor a housing or duct member 10 of tubular form having its opposite ends flanged as at 11 and 12. The upper flanged end 11 is mounted by a screw 13 over an opening 14 formed in the rear portion of the unit G above the propeller shaft and drive connections, and is so arranged that the housing 10 will communicate with the interior of the standard B as shown. The lower flanged end 12 of the housing 10 is then secured by a screw 15 over an opening 16 in the upper side of the rear portion of the unit G when it surrounds the propeller shaft J, so that the housing communicates with the open rear end of the unit. The housing is curved, as shown, in order to clear the pump O, and is formed of a rearwardly tapering or aerofoil cross section as shown in Fig. 3, in order to reduce water resistance and drag. A seal is formed at 17 (at its upper flanged end) with the unit G and a shoulder 18 engages the pump O, all of which assembly devices aid in properly locating and sealing the housing 10 in its connection with the transmission unit.

An anti-cavitation plate 19 is formed on the unit G and its rearward portion 19a is carried by the housing 10 to extend rearwardly over the propeller 20 for the usual purpose. Of course the entire assembly is "streamlined" and shaped to reduce resistance to its travel through the

water, and to facilitate steering of the boat to which the motor is attached.

The propeller 20 is of novel form in that it has the hollow trunco-conical hub 21 by which it is secured on the rear extremity of the propeller shaft J. This hub 21 has its larger open end turned forwardly and fitted rotatably over the open rear end of the transmission unit G, as indicated at 22, and openings or vents 23 are formed in the hub between the blades 24. The propeller is secured to the shaft J by the usual lock nut 25.

In operation the exhaust gases from the motor A are admitted to the upper end of the standard B in usual manner, and they flow downwardly through said member in the space existing therein around the drive shaft H, emerging from the opening 14. Ordinarily the gases are simply discharged at whatever location is convenient, but, for purpose of exhaust noise reduction, it is of course desirable to discharge the gases below the water level. However, this has heretofore led to difficulty due to the building up of back pressure in the exhaust system causing incomplete scavenging in the motor, and also the noise has been but slightly reduced. By the use of my invention as described, the gases are, however, now carried through the housing 10 and are discharged through the vents 23 out rearwardly of the hub of the propeller. Several advantageous actions now occur. It will be readily understood that the action of the propeller blades 24 in the water will cause the water immediately surrounding the propeller to be urged outwardly and, to some extent rearwardly from the blades. There results, then, the formation of at least a partial vacuum immediately to the rear of the propeller hub 21, and the exhaust gases emerging from the vents 23 flow into this relative vacuum. The action is such that the gases are in effect sucked from the hub with such force and rapidity that very complete scavenging will occur. Furthermore, the gases as they escape are co-mingled with the very turbulent water rearwardly of the propeller and are "broken up" to such extent that the exhaust noise is substantially eliminated, as will be evident.

In lieu of the propeller construction as just described, I may employ a propeller such as indicated at 20a in Fig. 4, where the hub 21a is hollow and substantially cylindrical or tubular and open from front to rear ends. The shaft J is then secured by the nut 25a in a smaller bearing 26 which is supported concentrically in the hub 21a by radially extended and angularly turned fan blades 27 which extend between the hub and bearing inside of the former. This type of propeller, when rotating, sets up a positive and powerful suction through its hub by action of the blades 27, such as will very forcefully draw out the exhaust gases and discharge them rearwardly from the hub. This action, supplemented as it is by the aforementioned vacuum formed behind the propeller hub, will positively scavenge the motor of all exhaust gases under all conditions.

It is understood that I may vary from the specific structures disclosed, provided that such variations fall within the spirit and scope of the appended claims.

Having thus fully disclosed my invention, what I claim as new and desire to secure by Letters Patent, is:

1. A boat propulsion apparatus comprising, an internal combustion motor, a propeller driven by

the motor and including a hollow hub member, blower fan blades in the said hub, and means for conducting exhaust gases from the motor to the hub whereby said gases will be discharged rearwardly through the hub by action of the blades therein.

5 2. A boat propulsion apparatus comprising, an internal combustion motor assembly including a housing member opening rearwardly and carrying exhaust gases from the motor, a propeller driven by the motor and having a hollow hub member rotating adjacent the said opening, and blower means in the said hub member for drawing the gases from the housing member and discharging them rearwardly from the propeller hub.

10 3. In a boat propulsion apparatus, a motor driven shaft of solid construction, a propeller having a hub mounted on the shaft for rotation thereby, means for conducting waste products of the motor to a point forwardly of the hub but radially outwardly of the shaft, and the said hub having a passage opening forwardly to receive

said products and opening rearwardly for the discharge of said products rearwardly through the hub.

15 4. In a boat propulsion apparatus, a motor driven shaft, a propeller mounted on the shaft and having a passageway outwardly thereof for the discharge of waste products from the motor, and propelling means in said passageway for acting on said products to facilitate their movement therethrough.

10 5. In a boat propulsion apparatus, means for mounting a propeller shaft on the boat, an internal combustion engine for driving the shaft, a propeller mounted on the shaft to be driven thereby and including a chambered hub having 15 vents opening rearwardly from the chamber, and means for delivering waste products of the motor rearwardly into the chambered hub but radially outwardly of the shaft, whereby said products may be discharged through the hub vents into 20 the water acted upon by the propeller.

ADOLPH RONNING.
